(57) **CLAIM**

The ornamental design for a key holder, as shown and described.

DESCRIPTION

1. Key holder

1.1 is a top, right side perspective view of a key holder showing my new design;

1.2 is a top view thereof;

1.3 is a bottom, left side view thereof;

1.4 is a bottom view thereof; and

1.5 is a front view thereof.

The broken line showing of keys in illustrations 1.1 and 1.3 is for the purpose of illustrating environmental structure and forms no part of the claimed design.
